UNITED STATES PATENT OFFICE.

FREDERICK B. TOWNSEND, OF CHICAGO, ILLINOIS, ASSIGNOR TO W. H. MINER COMPANY, OF CHICAGO, ILLINOIS, A CORPORATION OF ILLINOIS.

COMBINED FRICTION AND DIRECT-ACTING SPRING DRAFT-RIGGING FOR RAILWAY-CARS.

SPECIFICATION forming part of Letters Patent No. 757,579, dated April 19, 1904.

Application filed January 14, 1904. Serial No. 188,949. (No model.)

To all whom it may concern:

Be it known that I, FREDERICK B. TOWNSEND, a citizen of the United States, residing in Chicago, in the county of Cook and State 5 of Illinois, have invented a new and useful Improvement in a Combined Friction and Direct-Acting Spring Draft-Rigging for Railway-Cars, of which the following is a specification.

10 My invention relates to combined friction and direct-acting spring draft-rigging for railway-cars.

The object of my invention is to provide a combined friction and direct-acting spring draft-rigging of a simple, strong, efficient, and durable construction, the side plates or stop-castings of which may be of simple ordinary form and apply to the draft-timbers or center sills of the car in the usual manner 15 and which will operate effectually and reliably to cushion both pulling and buffing strains by the direct action of the spring when the strains are light and both by the frictional resistance and by the tension of the direct-acting spring when the strains are heavy.

My invention consists in the means I employ to practically accomplish this object or result—that is to say, it consists, in connection with the car-coupler, draw-bar, draw-bar extension, 20 and a pair of side plates or stop-castings having front and rear stops, of a transversely-acting spring and longitudinally-acting spring-followers, a pair of transversely-movable friction plates or blocks having oppositely-inclined friction-faces and a longitudinally-moving friction shell or case having a pair of oppositely-inclined friction-faces engaging the corresponding friction-faces on said friction plates or blocks, and a spring-seat interposed 25 between the rear end of the direct-acting spring and the rear follower and having flanges or shoulders engaging corresponding flanges or shoulders on the longitudinally-movable friction shell or case to restore the 30 same to position when the strain is removed and the direct-acting spring expands. The rear follower under pulling strains moves

the longitudinally-sliding friction shell or case with the draw-bar, while the front follower holds the transversely-movable friction plates or blocks from longitudinal movement and through them holds the middle follower also stationary, and thus compresses both the longitudinally-acting and the transversely-acting springs, the direct-acting spring having an initial compression due to the interposed spring-seat before the sliding friction shell or case begins to move, and under buffing strains the rear follower, after the direct-acting spring receives its initial compression, 35 holds the sliding friction shell or case stationary, while the front follower moves the transversely-movable friction plates or blocks longitudinally with the draw-bar and through them the middle follower also, and thus causes 40 both the longitudinally-acting and the transversely-acting springs to be compressed, and in both cases, pulling and buffing, the frictional resistance of the interengaging inclined friction-faces on the shell or case and on the 45 friction plates or blocks is added to the resistance of the springs.

My invention also consists in the novel construction of parts and devices and in the novel combinations of parts and devices here- 50 in shown and described.

In the accompanying drawings, forming a part of this specification, Figure 1 is a central vertical longitudinal section of a combined friction and direct-acting spring draft-rigging 55 embodying my invention. Fig. 2 is a horizontal section taken on the line 2 2 of Fig. 1. Fig. 3 is a cross-section on line 3 3 of Fig. 2. Fig. 4 is a detail perspective view of the interposed spring-seat. Fig. 5 is a detail perspective view of one of the transversely-movable friction plates or blocks, and Fig. 6 is a perspective view of the longitudinally-sliding 60 friction shell or case.

In the drawings, A A represent the center 65 sills of a car, A' the cross-sill, A² the buffer-plate, and A³ the carry-iron of a railway-car.

B is the draw-bar of the coupler B', and B² is the draw-bar extension, the same being pref-

erably in the form of a yoke or strap secured to the draw-bar by the rivet b and interengaging shoulders $b' b''$.

C, C', and C'' are the followers, and D D' are the side plates or stop-castings, the same having front and rear stops d d' for the front and rear followers to abut against and upper and lower guides $d'' d'''$, in or on which the followers and the sliding friction shell or case H reciprocate, the lower guide d''' being removably secured in place by a bolt d^4 to facilitate the insertion and removal of the draft-rigging.

E is a longitudinally-arranged spring between the middle and rear followers C' C'', a spring-seat K being interposed between the rear end of the spring E and the rear follower C'.

F is a transversely-arranged spring between the transversely-movable friction plates or blocks G G.

The transversely-movable friction plates or blocks G G have oppositely-inclined friction-faces g g , which bear against corresponding inclined friction-faces h h on the sliding or longitudinally-movable friction shell or case H, which is preferably rectangular in cross-section, as shown in the drawings. The longitudinally-movable friction shell or case H has an interior shoulder or flange h' at its rear end, which engages a corresponding exterior flange or shoulder h on the interposed spring seat or block K. The spring seat or block K projects through the rear end of the sliding friction shell or case H, and thus permits an initial or limited compression of the direct-acting spring E before the rear follower C'' engages the rear end of the sliding friction shell or case H. The transversely-movable friction plates or blocks G G are interposed between the front and middle followers C C', and the friction of their end faces g^2 g^3 against the followers C C' affords a material frictional resistance in addition to that produced by the friction of the inclined friction-faces g g against the similarly-inclined friction-faces h h of the shell or case H. The friction plates or blocks G G are chambered out at g^4 to give additional length or room for the transversely-acting spring F, thus forming inwardly-projecting end flanges g^5 g^6 at the front and rear ends of the friction blocks or plates G G. The interposed spring-seat block K not only serves to permit an initial or limited compression of the directly-acting spring E before the frictional resistance is brought into action, but also serves to restore the sliding friction-shell H to its normal position. Small springs e f may preferably be inclosed within the springs E and F, respectively.

60 I claim—

1. In a combined friction and direct-acting spring draft-rigging, the combination with a draw-bar, draw-bar extension, side plates or

stop-castings and followers, of a longitudinally-acting spring, a transversely-acting 65 spring, a pair of transversely-movable friction plates or blocks, a longitudinally-movable friction shell or case and a spring seat or block interposed between the rear end of the longitudinally-acting spring and the rear follower, 70 substantially as specified.

2. In a combined friction and direct-acting spring draft-rigging, the combination with a draw-bar, draw-bar extension, side plates or stop-castings and followers, of a longitudinally-acting spring, a transversely-acting 75 spring, a pair of transversely-movable friction plates or blocks, a longitudinally-movable friction shell or case and a spring seat or block interposed between the rear end of the longitudinally-acting spring and the rear follower, 80 said spring seat or block and said longitudinally-movable friction shell or case having interengaging shoulders, substantially as specified. 85

3. In a combined friction and direct-acting spring draft-rigging, the combination with a draw-bar, draw-bar extension, side plates or stop-castings and followers, of a longitudinally-acting spring, a transversely-acting 90 spring, a pair of transversely-movable friction plates or blocks having inclined friction-faces, a longitudinally-movable friction shell or case having inclined friction-faces engaging the inclined friction-faces of said transversely-movable friction plates or blocks, and a spring seat or block interposed between the rear end of the longitudinal spring and the rear follower, substantially as specified. 95

4. In a combined friction and direct-acting 100 spring draft-rigging, the combination with a draw-bar, draw-bar extension, side plates or stop-castings and followers, of a longitudinally-acting spring, a transversely-acting 105 spring, a pair of transversely-movable friction plates or blocks having inclined friction-faces, a longitudinally-movable friction shell or case having inclined friction-faces engaging the inclined friction-faces of said transversely-movable friction plates or blocks and a spring seat 110 or block interposed between the rear end of the longitudinal spring and the rear follower, said spring seat or block and said friction shell or case having interengaging shoulders to cause 115 said shell or case to return to its normal position as the longitudinal spring expands, substantially as specified.

5. The combination with a draw-bar, draw-bar extension, side plates or stop-castings and followers, of a transversely-acting spring, a longitudinally-acting spring, a pair of transversely-movable friction-blocks against which said transversely-acting spring bears, and having inclined friction-faces, a longitudinally-movable friction shell or case surrounding and taking the lateral thrust of said transversely- 125

movable friction-blocks and having inclined friction-faces engaging the inclined friction-faces of said transversely-movable friction-blocks, and connecting means between said 5 shell and the rear follower for causing said longitudinally-movable friction shell or case to return to its normal position when the lon-

gitudinally-acting spring expands, substantially as specified.
